2-SULFAMOYLBENZOIC ACID ESTERS

Glenn H. Hamor, University Park, Los Angeles 7, Calif.

No Drawing. Filed Mar. 11, 1959, Ser. No. 798,582

7 Claims. (Cl. 260—470)

This invention relates to new esters of 2-sulfamoylbenzoic acids which have useful pharmacodynamic activity.

The compounds of this invention are particularly useful as muscle relaxants as well as anticonvulsants and central nervous system depressants while possessing a minimum of side effects.

The novel 2-sulfamoylbenzoic acid esters of this invention are represented by the following structural formula:

Formula I

when R_1 and R_2 represent hydrogen or lower alkyl groups having 1 to 6 carbon atoms and R_3 represents a branched alkyl group having 3 to 6 carbon atoms, a cycloalkyl group having 4 to 6 carbon atoms or an unsaturated alkyl group having 3 to 6 carbon atoms.

Advantageous compounds of this invention are represented by the following structural formula:

Formula II

when R_3 represents a branched alkyl group having 3 to 6 carbon atoms.

A particularly advantageous and preferred compound of this invention is isopropyl 2-sulfamoylbenzoate which possesses superior muscle relaxant activity with a minimum of side effects.

Surprisingly the compounds of this invention have been found to have a higher order of muscle relaxant and anticonvulsant activity than the closest compounds of the prior art. For instance, the prior art compound most closely related structurally to the 2-sulfamoylbenzoate derivatives of this invention is ethyl 2-sulfamoylbenzoate whose structure is represented by Formula I when R_1 and R_2 are hydrogen and R_3 is ethyl [E. Shrader, J. Prakt. Chem., 95, 312-26 (1917); abstract, J. Chem. Soc., 112, I, 709-710 (1917)]. The Shrader reference does not disclose any pharmacodynamic activity for this ethyl ester. The compounds of this invention have been unexpectedly found to have a significant level of muscle relaxant activity with a low level of side effects while the prior art compound is much less active. For instance, in a standard test for muscle relaxant activity, namely protection against strychnine convulsions in mice, the ED_{50} for the ethyl ester of the prior art compound is 99 mg./kg. while the ED_{50} for the compound of this invention most closely related structurally, namely the isopropyl ester, is 50 mg./kg., at least twice as active. This is indeed surprising and unexpected.

The compounds of this invention are prepared according to the following synthetic procedures:

Procedure 1

Procedure 2

Procedure 3

According to Procedure 1 which is particularly useful for preparing branched alkyl esters of N-unsubstituted sulfamoylbenzoic acid, saccharin is treated with an excess of the appropriate alcohol in the presence of a mineral acid such as hydrochloric or sulfuric acid. The reaction mixture is heated at from about 60° C. to the reflux temperature of the alcohol for a period of about 16 to about 72 hours. Filtering the reaction mixture, concentrating the filtrate, dissolving the residue in an organic solvent such as ethyl acetate or ether, washing the organic solution with a dilute aqueous alkaline solution such as sodium or potassium bicarbonate solution and with water, drying with a drying agent such as anhydrous magnesium sulfate, filtering and concentrating in vacuo gives a solid material which is conveniently recrystallized from aqueous alcohol such as methanol or isopropanol to give the compounds of this invention.

According to Procedure 2 which is particularly advantageous in the preparation of compounds in which the ester group is unsaturated and/or the sulfamoyl group has one or two alkyl substituents, 2-sulfonylbenzoic anhydride (or acid) is converted to its dichloride by treatment with an excess of a chlorinating agent such as phosphorus trichloride, thionyl chloride or, preferably, phosphorus pentachloride. The reactants are heated, conveniently at reflux temperature for about two to about six hours. The reaction mixture is concentrated leaving crude 2-chlorosulfonylbenzoyl chloride as the residue. This dichloride is heated with an excess of the appropriate alcohol at about 40° to about 55° C. for about 16 to about 32 hours. The excess alcohol is removed in vacuo leaving the crude ester of 2-chlorosulfonylbenzoic acid. Treatment of this 2-chlorosulfonyl compound in an organic solvent such as ether or benzene with an excess of ammonia or an alkylamine and allowing the mixture

to stand for about 24 to about 48 hours yields, upon filtration and concentration of the mixture, the 2-sulfamoylbenzoates of this invention.

According to Procedure 3 which is a particularly advantageous procedure for the preparation of cycloalkyl esters of 2-sulfamylbenzoic acid in which the sulfamyl group may optionally have alkyl substituents, 2-sulfonylbenzoic anhydride is treated with an excess of the appropriate alcohol at about 35° to about 50° C. for approximately 4 to 8 hours. Removal of the excess alcohol in vacuo leaves, as the residue, the 2-sulfonylbenzoate which is treated with a chlorinating agent such as phosphorus trichloride, thionyl chloride or, preferably, phosphorus pentachloride. The reactants are heated, conveniently at reflux temperature, for about two to about four hours. Concentration of the reaction mixture gives, as the residue, the ester of 2-chlorosulfonylbenzoate which is treated with an excess of ammonia or an alkylamine in an organic solvent such as ether or benzene. The reaction mixture is allowed to stand for about 24 to about 48 hours, then worked up, conveniently, by filtering and concentrating the filtrate to give the 2-sulfamoylbenzoate of this invention.

The following examples are not limiting but are illustrative of compounds of this invention and will serve to make fully apparent all the compounds embraced by the general formula given above.

Example 1

A suspension of 45.8 g. of saccharin in 200 ml. of isopropanol immersed in an ice bath is saturated with hydrogen chloride. The mixture is heated in a pressure bottle at 70° C. for three days, then filtered. The filtrate is concentrated in vacuo and the residue is dissolved in ethyl acetate and washed with 5% aqueous sodium bicarbonate and with water. The solution is dried over anhydrous magnesium sulfate, filtered and concentrated in vacuo to give a white solid which is recrystallized from aqueous methanol to give isopropyl 2-sulfamoylbenzoate, M.P., 72-75° C.

Example 2

A mixture of 40 g. of saccharin, 20 drops of concentrated sulfuric acid and 200 ml. of isobutyl alcohol is refluxed for 16 hours. The reaction mixture is filtered and the filtrate is concentrated in vacuo. The residue is taken up in ethyl acetate, washed with 5% aqueous sodium bicarbonate solution and with water. The ethyl acetate solution is dried over magnesium sulfate, filtered and concentrated in vacuo. The white solid residue is recrystallized from aqueous methanol to give isobutyl 2-sulfamoylbenzoate.

Example 3

A mixture of 50.0 g. of 2-sulfonylbenzoic anhydride and 100.0 g. of phosphorus pentachloride is refluxed for two hours. Low boiling material is removed in vacuo, leaving as the residue crude 2-chlorosulfonylbenzoyl chloride.

Five grams of this dichloride is heated in 50 ml. of isopropanol at 50° C. for 2 hours. The excess alcohol is removed in vacuo. The residue, crude isopropyl 2-chlorosulfonylbenzoate, is dissolved in ether and added to an ether solution containing 3.0 g. of methylamine. The resulting mixture is allowed to stand at room temperature for 24 hours, then filtered and the excess methylamine is removed in vacuo. The ethereal residue is washed with water and dried over anhydrous magnesium sulfate. On standing, a precipitate of N-methylsaccharin deposits and is filtered off. Concentration of the filtrate gives the isopropyl 2-(N-methylsulfamoyl)-benzoate as a viscous yellow oil.

Example 4

A mixture of 10.0 g. of 2-chlorosulfonylbenzoyl chloride, prepared as in Example 3, and 75 ml. of isopropanol is heated at 45° C. for 24 hours. The excess alcohol is removed in vacuo. The residue, crude isopropyl 2-chlorosulfonylbenzoate, is dissolved in ether and then added to

7.0 g. of dimethylamine in ether solution. The resulting mixture is allowed to stand for 36 hours, then filtered. The excess dimethylamine is removed in vacuo. The ethereal residue is washed with water, dried and stripped of solvent to give isopropyl 2-(N,N-dimethylsulfamoyl)-benzoate, an orange viscous oil.

Example 5

To an ether solution of 5.0 g. of isopropyl 2-chlorosulfonylbenzoate, prepared as in Example 4, is added 5.0 g. of hexylamine in ether solution. The resulting mixture is allowed to stand for 36 hours, then filtered. The mixture is concentrated in vacuo. The residue is isopropyl 2-(N-hexylsulfamoyl)-benzoate.

Example 6

An ethereal solution of 5.0 g. of dihexylamine is added to an ether solution of 5.0 g. of isopropyl 2-chlorosulfonylbenzoate, prepared as in Example 4. The resulting solution is allowed to stand at room temperature for 36 hours. Working up as in Example 5 yields isopropyl 2-(N,N-dihexylsulfamoyl)-benzoate.

Example 7

A mixture of 30.0 g. of saccharin in 200 ml. of 2-hexanol and 0.5 ml. of concentrated sulfuric acid is refluxed for 20 hours. The reaction mixture is filtered and the filtrate is concentrated in vacuo. The residue is dissolved in ethyl acetate, washed with 50% aqueous sodium bicarbonate solution and with water. The ethyl acetate solution is dried, filtered and evaporated in vacuo. The residue is 2-hexyl 2-sulfamoylbenzoate.

Example 8

Ten grams of 2-chlorosulfonylbenzoyl chloride, prepared as in Example 3, is heated at 45° C. with 50 ml. of allyl alcohol for 4 hours. The excess allyl alcohol is removed in vacuo. The residue is dissolved in ether and added to 3.0 g. of ammonia in ether. The resulting mixture is allowed to stand at room temperature for 36 hours, then filtered and concentrated to give as the oily residue, allyl 2-sulfamoylbenzoate.

Example 9

A mixture of 5.0 g. of 2-chlorosulfonylbenzoyl chloride, prepared as in Example 3, and 25 ml. of propargyl alcohol is heated at 50° C. for 4 hours. The excess alcohol is removed in vacuo and the residue is taken up in ether. This ethereal solution is added to 2.0 g. of ammonia in ether and the resulting solution is allowed to stand at room temperature for 36 hours. Filtration and concentration of the filtrate gives propargyl 2-sulfamoylbenzoate.

Example 10

Methallyl alcohol (30 ml.) and 4.0 g. 2-chlorosulfonylbenzoyl chloride, prepared as in Example 3, are heated at 45° C. for 4 hours. The excess alcohol is evaporated in vacuo. The residue, dissolved in ether, is added to 2.0 g. of ammonia in ether. The resulting solution is allowed to stand for 36 hours, then filtered and the filtrate concentrated to give, as the residue, methallyl 2-sulfamoylbenzoate.

Example 11

A mixture of 5.0 g. of 2-chlorosulfonylbenzoyl chloride, prepared as in Example 3, and 50 ml. of 5-hexen-1-ol is heated at 50° C. for 6 hours. The excess alcohol is removed in vacuo and the residue is dissolved in ether and added to 50 ml. of an ether solution saturated with ammonia. The resulting mixture is allowed to stand for 36 hours, then filtered. The filtrate is concentrated to give as the residue 5-hexenyl 2-sulfamoylbenzoate.

Example 12

Three grams of o-sulfonylbenzoic anhydride are dissolved in 15 ml. of cyclobutanol by gentle warming. The solution is heated at 40° C. for six hours, then the excess

cyclobutanol is removed in vacuo. The resulting oily solid, cyclobutyl 2-sulfobenzoate, is heated at reflux with 5.0 g. of phosphorus pentachloride for three hours. The phosphorus oxychloride which forms is removed in vacuo and the residue dissolved in ether and washed with ice water. The ethereal solution of cyclobutyl 2-chlorosulfonylbenzoate is treated with 5.0 g. of anhydrous ammonia. The resulting mixture is allowed to stand at room temperature for 24 hours, then filtered. The filtrate is evaporated leaving an oil which solidifies on treatment with water. Recrystallization of this solid material from aqueous isopropanol gives cyclobutyl 2-sulfamoylbenzoate as a white solid.

Example 13

A mixture of 3.0 g. of o-sulfobenzoic anhydride and 10 ml. of cyclopentanol is heated at 40° C. for six hours. The excess alcohol is removed in vacuo to give, as the residue, cyclopentyl 2-sulfobenzoate which is then refluxed with 5.0 g. of phosphorus pentachloride for three hours. Working up the mixture as in Example 12, treating the resulting cyclopentyl 2-chlorosulfonylbenzoate in ether solution with excess ammonia and working up this mixture as in Example 12 gives cyclopentyl 2-sulfamoylbenzoate which is recrystallized from isopropanol-water.

Example 14

Four grams of o-sulfobenzoic anhydride is heated with 20 ml. of cyclohexanol at 40° for six hours. The excess cyclohexanol is removed in vacuo to give, as the residue, cyclohexyl 2-sulfobenzoate which is refluxed with 7.0 g. of phosphorus pentachloride for three hours. The phosphorus oxychloride which forms is removed in vacuo. The residue is dissolved in ether and washed with ice water. The ethereal solution of cyclohexyl 2-chlorosulfonylbenzoate is treated with 5.0 g. of ethylamine in ether solution. After standing for 24 hours, the mixture is filtered and the filtrate evaporated. The residue solidifies on treatment with water and is recrystallized from isopropanol-water to give cyclohexyl 2-(N-ethylsulfamoyl)-benzoate.

Example 15

A mixture of 35.0 g. of saccharin, 20 drops of concentrated sulfuric acid and 200 ml. of sec-butyl alcohol is refluxed for 16 hours. The reaction mixture is filtered and concentrated in vacuo. The residue is dissolved in ethyl acetate, washed with 5% aqueous sodium bicarbonate and with water. Drying the ethyl acetate solution over magnesium sulfate, filtering, concentrating in vacuo and re-

crystallizing the residue from aqueous methanol gives sec-butyl 2-sulfamoylbenzoate.

Example 16

5 Five grams of o-sulfobenzoic anhydride are dissolved in 25 ml. of t-butyl alcohol by gentle warming. Heating the solution at 45° C. for six hours and removing the excess t-butanol in vacuo gives, as the residue, t-butyl 2-sulfobenzoate which is then refluxed with 10.0 g. of phosphorus pentachloride for four hours. The mixture is concentrated in vacuo and the residue is dissolved in ether, washed with water and treated with 7.0 g. of anhydrous ammonia. The resulting mixture is allowed to stand at room temperature for 24 hours, then filtered. The filtrate is evaporated, leaving t-butyl 2-sulfamoylbenzoate as the residue.

What is claimed is:

1. A chemical compound having the structural formula:

20

in which R₁ and R₂ are members selected from the group consisting of hydrogen and lower alkyl and R₃ is a member selected from the group consisting of a branched alkyl group having from 3 to 6 carbon atoms, a cycloalkyl group having from 4 to 6 carbon atoms and an unsaturated acyclic hydrocarbon group having from 3 to 6 carbon atoms.

25 30 35 40 45 50 55 60 65 70 75 80 85 90 95 100

2. A chemical compound having the structural formula:

35

in which R₃ is a branched alkyl group having from 3 to 6 carbon atoms.

3. Isopropyl 2-sulfamoylbenzoate.
4. Tertiary butyl 2-sulfamoylbenzoate.
5. Secondary butyl 2-sulfamoylbenzoate.
6. Allyl 2-sulfamoylbenzoate.
7. Propargyl 2-sulfamoylbenzoate.
